UNITED STATES PATENT OFFICE.

STANLEY B. GAMBLE, OF OAKLAND, CALIFORNIA.

FLOUR SIFTER.

Application filed September 30, 1925. Serial No. 59,451.

To all whom it may concern:

Be it known that I, STANLEY B. GAMBLE, a subject of the King of Great Britain, and a resident of Oakland, in the county of Alameda and State of California, have invented certain new and useful Improvements in Flour Sifters, of which the following is a specification.

My invention relates to sifters for flour and the like, and it has especial reference to a sifter of the type adapted to be held in one hand of an operator while the other hand is free to perform other work in connection with the sifted product.

Sifters, which have heretofore been devised for operation by one hand alone, comprise a number of parts so arranged that the operation of such sifters is heavy and too tiresome for average housekeepers.

The principal object of my invention is to construct a sifter of as few parts as possible and to arrange the parts in such a manner that the sifter can be operated by the pressure of one finger of a person's hand while the same hand holds the handle.

Another object of the invention is to construct a sifter in such manner that, when the sifter is operated, the sifted product is confined to a concentrated and comparatively small area below the sifter, not scattered in all directions over a comparatively large area, as is done by such sifters as are operated by being shaken vertically or horizontally by the hand in which this type of sifter is held.

Other objects and advantages of my invention will be understood from the following detailed description of the accompanying drawings, which illustrate a preferred embodiment of the invention.

In the drawings:

Figure 1 is a plan of the sifter constructed in accordance with my invention; and

Fig. 2 is a side elevation of it;

Fig. 3 is a sectional elevation of the container and the sieve therein and shows the actuating element in depressed position. The dash-and-dot lines indicate a person's hand holding the sifter and also the position to which the actuating element is returned when the pressure on the actuating element is released; and

Fig. 4 is a fragmental elevation at an angle of 90 degrees from that in Fig. 3, and shows the actuating element engaging the arm of the sifting member and being held

in normal position by the spring. Dash-and-dot lines show the arm in its lowermost position and also the arc of a circle described by the end thereof during its movement to and from such position.

My invention comprises a sifter 5 in which a container 6 has mounted on its outside a handle 7, and within the container is mounted a sieve 8 having a concave upper surface 9. Above the sieve is pivotally mounted within the container a sifting member 10, and the main body thereof is in this instance shown as comprising three branches 13, which are formed to substantially conform to the shape of the upper surface 9 of the sieve. Relative to a horizontal plane drawn through the container and the center of the handle 7, as is shown in dash-and-dot lines in Fig. 1, the axis of the sifting member 10, as defined by its pivots 11 and 12, is oblique, so that an arm 14, forming an extension of the pivot 12 and being at an angle to said axis, may extend within the handle 7.

A loop 15, formed in an element 16 reciprocatingly mounted in the handle 7, engages the arm 14 so that the arm is actuated by the reciprocating motion of the element 16 and thus also the sifting member 10 is oscillated over the concave surface 9 of the sieve 8. In order that the element 16 may be conveniently operated by one finger, preferably the thumb of a person's hand that holds the handle 7, as shown in dash-and-dot lines in Fig. 3, the upper end of the element is provided with a finger rest 17, which also serves as a stop adapted to abut against the upper portion of the handle 7 in order to determine the extreme depressed position of the element. In this instance the finger rest is shown simply as a loop portion at right angles to the stem of the element, and the lower end of the element may be provided with a stop 18 adapted to abut against the underside of the handle 7 when the element is in its normal position. For the purpose of returning the actuating element 16 from its depressed position as shown in full lines in Fig. 3, to its normal position as shown in full lines in Fig. 2 and in dash-and-dot lines in Fig. 3, a coil spring 19 is suitably hooked with its lower end in the loop 15 of the element and with its upper end into an opening formed in the upper part of the handle 7.

It is understood from the foregoing that, when the actuating element 16 is in normal

position, the arm 14 of the sifting member 10 is held in the position shown in full lines in Fig. 4, thereby holding the sifting member in the position shown in full lines in Fig. 1, and, when the element is in its extreme depressed position, the arm is in the position shown in dash-and-dot lines in Fig. 4, thus holding the sifting member in the extreme reversed position indicated by the dash-and-dot lines 13' of one of its side branches.

By alternately depressing the element 16 with one finger of the same hand that holds the handle 7 and releasing the pressure so as to allow the spring 19 to return the element to its normal position, it is thus seen that the sifting member is oscillated over the sieve 8. It is further to be observed that, since the movement back and forth of the sifting member may be accomplished with a comparatively small horizontal movement, if any, of the container 6, the flour or other product sifted through the sifter 5 may be concentrated over a spot, so to speak. This makes my sifter particularly useful for flour sifting, as often small bowls are used, in which the flour is stirred after sifting, so that the operator, while using the sifter with one hand, has the other hand free for stirring and mixing the flour with other ingredients in the bowl.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made, when desired, as fall within the scope of the appended claims.

Having thus described my invention, I claim as new and desire to secure by Letters Patent of the United States the following:—

1. A sifter adapted for sifting flour or the like, said sifter comprising a container having a handle mounted on the outside thereof; a sieve mounted in the container, said sieve having an upper concave surface; a sifting member pivotally secured in the container for moving back and forth on said sieve surface and provided with an arm adapted to swing within said handle; an element mounted in said handle and engag-

ing said arm for actuating the sifting member, said element being adapted to move downwardly from normal position by the pressure of one finger of a person's hand while the same hand holds the handle; and a coil spring having its upper end attached to the upper part of the handle and its lower end attached to said element for returning the element from depressed to normal position.

2. A sifter adapted for sifting flour or the like, said sifter comprising a container having a handle mounted on the outside thereof; a sieve mounted in the container, said sieve having an upper concave surface; a sifting member pivotally secured in the container for moving back and forth on said sieve surface and provided with an arm adapted to swing within said handle; an element mounted in said handle and engaging said arm for actuating the sifting member, said element being adapted to move downwardly from normal position by the pressure of one finger of a person's hand while the same hand holds the handle; and a coil spring having its upper end attached to the upper part of the handle and its lower end attached to said element for returning the element from depressed to normal position, and stop means for limiting the movement of said element to either position.

3. A sifter adapted for sifting flour or the like, said sifter comprising a container having a handle mounted on the outside thereof; a sieve mounted in the container, said sieve having an upper concave surface; a sifting member pivotally secured in the container for moving back and forth on said sieve surface and provided with an arm adapted to swing within said handle; an element mounted in said handle and engaging said arm for actuating the sifting member, said element being adapted to move downwardly from normal position by the pressure of one finger of a person's hand while the same hand holds the handle; and a coil spring having its upper end attached to the upper part of the handle and its lower end attached to said element for returning the element from depressed to normal position, and stop means for limiting the movement of said element to either position, said means comprising a finger rest at the upper end of said element and a stop at the lower end thereof.

In testimony whereof, I affix my signature.

STANLEY B. GAMBLE.
